Primary Examiner — Catherine S Posthauer*Assistant Examiner* — Christine Marie Achen Zimmerman(57) **CLAIM**

The ornamental design for a slushie maker as shown and described.

DESCRIPTION

FIG. 1 is a top perspective view of a slushie maker showing my new design;

FIG. 2 is a bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is an enlarged view of a portion labeled as “9” on FIG. 1; and,

FIG. 10 is an enlarged view of a portion labeled as “10” on FIG. 1.

The dot-dash broken lines represent the designation of enlargement views and form no part of the claimed design.

1 Claim, 10 Drawing Sheets(56)
